UNITED STATES PATENT OFFICE.

JACOB M. HANSEN, OF CHICAGO, ILLINOIS, ASSIGNOR TO HARTMANN-MALCOLM COMPANY, OF CHICAGO, ILLINOIS, A CORPORATION OF ILLINOIS.

DESIGN FOR A STUMP FOR A SETTEE FRAME OR THE LIKE.

Application filed July 7, 1928. Serial No. 27,405. Term of patent 3½ years.

To all whom it may concern:

Be it known that I, JACOB M. HANSEN, a citizen of the United States, residing at Chicago, in the county of Cook and State of Illinois, have invented a new, original, and ornamental Design for a Stump for a Settee Frame or the like, of which the following is a specification, reference being had to the accompanying drawing, forming a part thereof.

The figure is a perspective view of a stump for a settee frame or the like showing my new design.

I claim:

The ornamental design for a stump for a settee frame or the like.

In witness whereof, I hereunto subscribe my name, this 2nd day of July, 1928.

JACOB M. HANSEN.
